RULING MACHINE

Filed Jan. 13, 1922

Inventor:
George F. McAdams.
By attorney
Frank Ward

UNITED STATES PATENT OFFICE.

GEORGE F. McADAMS, OF BROOKLYN, NEW YORK.

RULING MACHINE.

Application filed January 13, 1922. Serial No. 528,950.

To all whom it may concern:

Be it known that I, GEORGE F. McADAMS, a citizen of the United States, and resident of the borough of Brooklyn, city and State of New York, have invented a new and useful Improvement in Ruling Machines, of which the following is a specification.

My invention relates particularly to an auxiliary ruling head adapted for attachment to a ruling machine in proximity to the main ruling head, whereby additional lines, as for instance lines of another color, as head lines, marginal lines, box headings, etc., may be applied to either or both sides of the sheet or web immediately after the main ruling head has ruled its lines upon the same.

When additional lines have been ruled by separate discs of the main ruling head of the ruling machine, it has required the placing of the inking devices for the separate discs which ruled the underside of the paper, in a very inaccessible and inconvenient place under the feeding device. By this present invention I have been able to place the auxiliary ruling discs on separate shafts alongside of the main ruling discs and thus be able to place the upper and lower inking devices for said auxiliary ruling discs close together on one side of the discs in plain sight and very accessible for ink supply, wick adjustment, etc. Also by providing the shafts of the auxiliary ruling head with bearers at different points along the same, I am enabled to properly space the shafts and thus to mount on the same shafts both the discs and their grooved impression rollers for ruling additional lines on either or both sides of the paper and also coating discs arranged edge to edge for simultaneously ruling opposite additional lines on both sides of the paper; all of which ruling discs may be adjusted along their respective shafts to any desired position with respect to the discs of the main ruling head, to bring these additional lines into correct distances and locations with respect to the main ruled lines.

A practical embodiment of my invention is represented in the accompanying drawings, in which—

Fig. 1 represents the auxiliary ruling head in top plan.

Fig. 2 represents the same in end elevation, a portion of the main ruling head being shown.

Fig. 3 represents a back view of the auxiliary ruling head.

Fig. 4 represents a section taken in the plane of the line IV—IV of Fig. 3, showing also a portion of the main ruling head. 60

Fig. 5 represents one of the inking devices in top plan.

Fig. 6 represents the same in end elevation.

Fig. 7 represents the same in front elevation. 65

Fig. 8 represents the same in back elevation.

Fig. 9 represents a section taken in the plane of the line IX—IX of Fig. 8. 70

The auxiliary ruling head which is adapted to be removably attached to the ruling machine in back of and in proximity to the main ruling head, includes the side frames 1 and 2 in which are mounted upper and lower rotary shafts 3 and 4. These upper and lower shafts not only carry one or more pairs of ruling discs 5 and their grooved impression rollers 6, but also carry one or more pairs of ruling discs 5* arranged edge 75 to edge. The discs and grooved impression rollers are arranged for ruling additional lines on either or both sides of the web or sheet and the pairs of ruling discs 5* are arranged for simultaneously ruling opposite 80 lines upon both sides of the web or sheet. 85

Pairs of bearers 3*, 4*, arranged at different points along the shafts 3 and 4 serve to properly space the coating discs with their impression rollers and the coating discs arranged edge to edge to secure the correct impression for ruling. 90

The discs 5 and their grooved impression rollers 6 may be adjusted laterally along the shafts to different positions with respect 95 to the discs of the main ruling head of the machine, any suitable means being provided for securing the discs of the impression rollers in their adjusted positions. In the present instance, collars 5*** are slidable on the split disc sleeves 5** and collars 6* are slid- 100 able on the split impression roller sleeves 6** to clamp and release the discs and impression rollers, as is common. The said split sleeves are tapered and the movement of the collars on the sleeves clamps and unclamps the sleeves from the shaft. It will be apparent that the said discs and rollers are rigidly secured to the sleeves. 105

A crossbar 7 extends across the auxiliary 110

ruling head and on this crossbar I provide guides 8 for supporting the sheets or web as they pass through the auxiliary ruling head.

The upper and lower inking devices for 5 the ruling discs are located adjacent to each other to the rear of the auxiliary discs and are adjustable laterally to suit the positions of the said discs.

The auxiliary ruling head is provided 10 with upper and lower trough-like supports 9 and 10 which extend across the same to the rear of and in close proximity to their respective upper and lower shafts 3 and 4, the lower support 10 being preferably permanently placed and the upper support being removable. In the present instance I have provided the side frames 1 and 2 of the auxiliary ruling head with dowels 11 and 12 which are arranged to project upwardly 15 through the ends of the upper support 9.

Each inking device is herein shown as comprising an ink fountain 13 of general rectangular form provided along one of its sides with a spring 14 for removably holding the fountain in its laterally adjusted position. The inking roller 15 is mounted in the upper ends of a bracket 16, rising from the fountain 13, which bracket serves to 20 yieldingly hold the inking roller against its auxiliary ruling disc for applying ink thereto. A wick 17 is arranged to feed the ink from the fountain 13 to the inking roller 15 by capillary action. In the present instance I have provided a bracket 18 in position to 25 yieldingly hold the wick against the face of the inking roller 15. To prevent the wick from becoming displaced by its frictional contact with the inking roller, I provide the bracket 18 with slots 19, through which the 30 wick is threaded.

The upper and lower shafts 3 and 4 of the auxiliary ruling head may be driven from the ruling machine through the train of gears 20, 21, 22, and 23. The auxiliary ruling head in the present instance is removably attached to the ruling machine frame 24 which carries the discs 25, 26 of the main 45 ruling head by screws 27, 28.

From the above description it will be 50 seen that I have provided an auxiliary ruling head for ruling the additional lines such as head lines, marginal lines, box headings, etc. in any desired color and in any desired relationship to the lines ruled by the main ruling head of the machine on either or both sides of the web or sheet, and that I am also enabled to so locate the inking devices for the auxiliary ruling discs that access to 55 said inking devices may be readily obtained. Also it will be seen that I am enabled by the use of spacing bearers on the two auxiliary shafts to provide on the shafts not only a disc coacting with a grooved impression roller for ruling one one side of the web or 60 sheet, but also two discs arranged edge to 65

edge for ruling opposite lines on both sides thereof, the said discs being adjustable laterally to different positions with respect to the discs of the main ruling head.

It is evident that various changes may be 70 resorted to in the construction, form and arrangement of the several parts without departing from the spirit and scope of my invention; hence I do not wish to limit myself to the particular embodiment herein 75 shown and described, but

What I claim is:—

1. In a ruling machine, the main ruling head, and an auxiliary ruling head comprising upper and lower shafts, said auxiliary ruling head being operatively connected with the main ruling head, ruling discs and their impression rollers mounted on said shafts and adjustable laterally with respect to the main head ruling discs to bring the 85 additional lines into the required positions relative to the main ruled lines.

2. In a ruling machine, the main ruling head and an auxiliary ruling head comprising upper and lower shafts, said auxiliary ruling head being operatively connected with the main ruling head, ruling discs and their impression rollers mounted on said shafts and adjustable laterally with respect to the main head ruling discs to bring the 90 additional lines into the required positions relative to the main ruled lines, and upper and lower inking devices for said auxiliary ruling discs located on the same side of said discs in close proximity to each other. 100

3. In a ruling machine, the main ruling head and an auxiliary ruling head operatively connected with the main ruling head, said auxiliary ruling head comprising upper and lower shafts having mounted thereon both coacting discs and impression rollers for ruling on either or both sides of the paper and also coacting discs arranged edge to edge for simultaneously ruling opposite 105 lines on both sides of the paper. 110

4. In a ruling machine, the main ruling head and an auxiliary ruling head operatively connected to the main ruling head, said auxiliary ruling head comprising upper and lower shafts having mounted thereon both coacting discs and impression rollers for ruling on either or both sides of the paper and also coacting discs arranged edge to edge for simultaneously ruling opposite 115 lines on both sides of the paper, and upper and lower inking devices for the auxiliary discs arranged adjacent to each other on the same side of the discs. 120

5. In a ruling machine, the main ruling head and an auxiliary ruling head operatively connected to the main ruling head, said auxiliary head comprising upper and lower shafts, provided with spacing bearers at different points along the same and having mounted on said shafts both coacting discs 125 130

and impression rollers for ruling on either or both sides of the paper, and coacting discs arranged edge to edge for simultaneously ruling opposite lines on both sides of the paper, said auxiliary discs being adjustable laterally to different positions relative to the main head ruling discs.

6. In a ruling machine, the main ruling head and an auxiliary ruling head 10 relatively connected to the main ruling head, said auxiliary ruling head comprising upper and lower shafts provided with spacing bearers at different points along the same and having mounted on said shafts both 15 coacting discs and impression rollers for rul-

ing on either or both sides of the paper and coacting discs arranged edge to edge for simultaneously ruling opposite lines on both sides of the paper, said auxiliary discs being adjustable laterally to different positions relative to the main head ruling discs, and laterally adjustable upper and lower inking devices for the auxiliary discs arranged adjacent to each other on the same side of said discs.

In testimony, that I claim the foregoing as my invention, I have signed my name this 29th day of December, 1921.

GEORGE F. McADAMS.
